UNITED STATES PATENT OFFICE

2,296,025

IGNITION AND CONTROL MEANS FOR FUEL
BURNERS

John C. English, Cedar Rapids, Iowa, assignor to
Johnson Gas Appliance Company, Cedar Rap-
ids, Iowa, a corporation of Delaware

Application June 28, 1939, Serial No. 281,549

2 Claims. (Cl. 158—117.1)

This invention relates to fluid fuel burners and has particular relation to an ignition and control means for such burners.

It is the usual practice in many types of gas heating devices adapted for intermittent use to utilize a constant burning pilot light for igniting the gas issuing from the main burner. However there are numerous difficulties with this ignition system, among which are the cost of the gas burned by the pilot light when its heat is wasted, and the cost of servicing such ignition devices, as for instance lighting the pilot burner in the fall and turning it out in the spring, as well as lighting it in the event of the pilot light going out.

Also the pilot light is not altogether reliable since only a small amount of gas is used and the pilot light may go out. Also fouling of the light may occur to cause disagreeable odors and the like.

Other ignition systems have been proposed utilizing electricity for ignition purposes, but these systems have not been altogether satisfactory for the reason that the switches may stick or they may be located in the heat zone and corroding of the contacts may occur. Manual ignition may be employed of course, but this entails danger by reason of explosion, asphyxiation and the like, as well as lower efficiency by reason of the doors or the like necessary for manual ignition.

In other types of heating systems valves are employed for controlling the flow of fuel, but it is practically impossible to connect up any sort of electrical system to these valves to thereby provide an ignition means which will operate when the fuel flow valve is open or closed.

It is therefore among the objects of my invention to provide an ignition and control means for gas burners and the like which shall overcome the difficulties of the devices above mentioned and which will eliminate the necessity for manual lighting or a constant burning pilot light.

It is another object of my invention to provide ignition and control means for automatically lighting a fluid fuel burner without danger of explosion or injury to the operator, which means shall be "fool proof" and in which the failure of any of the parts of the mechanism to function results only in stopping the series of operations leading to ignition of the gas issuing from the main burner.

Another important object of my invention is to provide a quick acting ignition and control means in which heat sensitive portions of the

system may be located outside the burner chamber.

Another object of my invention is to very materially reduce the amount of wiring required in electrical igniting devices.

Another object of my invention is to provide an ignition and control system which is in operative unless there is sufficient gas pressure to operate the main burner.

Another object of my invention is to provide means for igniting a gas burner or the like without the necessity of using doors or other apertures to furnish a means of reaching the burner from outside the heating device.

Other and further features and objects of my invention will be more apparent to those skilled in the art upon a consideration of the accompanying drawing and following specifications, wherein is disclosed a single exemplary embodiment of the invention, with the understanding, however, that such changes may be made therein as fall within the scope of the appended claims, without departing from the spirit of the invention.

Figure 1 of the drawing is a schematic diagram illustrating one embodiment of my invention and how it may be used in connection with a gas burner, and

Figure 2 is a schematic drawing showing a modified form of the switch shown in Figure 1.

Referring now to the drawing:

The device there shown is particularly suitable for use with gas burners but quite obviously may be modified for other burners and other purposes.

The main portion of the control means is preferably located within the oven or other burner chamber adjacent the burner. This main portion includes a body 10, more or less rectangular in form. The body 10 has a supply inlet in the lower face thereof indicated at 11. This supply line can of course be brought in from the side as well as the bottom of the block-like base 10. The inlet 11 leads into a cylindrical chamber 12. Concentric with the outer chamber 12, is a smaller inner chamber 13. The wall of the channel between the chambers 12 and 13 is beveled, as indicated at 14, to form a valve seat for a valve 16. The valve is normally seated against the valve seat 14 to close the passageway between the chambers 12 and 13.

The valve stem 17 of valve 16 projects on through the opposite wall of the base member 10. This stem has an enlarged cylindrical portion 18 outside the body 10, and the portion 18

has a notch 19 therein for the purpose of receiving the free end of a bi-metallic strip as herein-after explained.

A U-shaped bi-metallic member 21 is secured to one end wall of the base member 10 by means of the bolt 22, and the free end of the U-shaped bi-metallic member is received within the notch 19 of the member 18, as indicated at 23. It is apparent that differential expansion and contraction of the two layers of dissimilar metals, which constitute the structure of the bi-metallic strip, will cause reciprocation of the valve stem 17 to raise and lower the valve 16 from its seat 14. The bi-metallic strip is so constructed and arranged that heating of the loop of the strip, as by means of the flame issuing from a pilot burner 24, will cause contraction of the loop to drive the stem inwardly to raise the valve 16 from its seat. When this is done the gas admitted at the inlet or supply 11 passes through the chamber 12, into the chamber 13, out through the outlet 26, through the conduit 21, and out through the main burner 28.

Ignition for the pilot burner 24 is furnished by means including an electrode 31. This electrode 31 is supported by means of a bracket 32 from the base 10. The electrode is of course insulated from the bracket. Current for causing a high voltage discharge through the gap 33 is furnished by means of the step-up transformer 34.

The primary of the step-up transformer 34 is grounded by means of the terminal 36 to the body or casing of a mercury switch indicated generally at 37. A connection is thus made between the terminal 36 and a pool of electrically conductive liquid, such as mercury, indicated at 38. An alternative arrangement, indicated by the dotted lines, in the event that a non-metallic switch casing is employed, is to directly connect the primary of the transformer to an electrode 39 extending into the mercury pool.

The other side of the primary coil is connected to the secondary 41 of a step-down power transformer 42, power being furnished by means of the line connection 43. The other side of the secondary coil 41 of the power transformer is connected to the central electrode 45 of the mercury switch 37. This central electrode 45 is, under normal conditions, spaced above the mercury pool 38 so that no electrical contact therewith is made.

There are two chambers 44 and 46 within the switch casing 37. The upper chamber communicates with the lower by means of a tube 47 which projects down from the upper chamber into the lower chamber and into the mercury pool 38. The central electrode 45 projects downwardly from the insulated cap 50 to a position within this tube.

The lower chamber 44 is connected by means of a conduit 48 to a channel 49 in the body 10. The mercury switch 37 is located outside of the oven or other enclosure in which the burner is located, the conduit 48 passing through the wall 51 of the enclosure. The conduit or channel 49 within the base 10 communicates with the chamber 12 and is also connected with the pilot burner orifice 54. When gas under pressure is present in the chamber 12, it will pass outwardly through the restricted orifice 54 and will also set up a pressure in the conduit 48 and the lower chamber 44 of the mercury switch. The upper chamber 46 of the mercury switch is connected

by means of a second conduit 52 with the inner chamber 13.

Now it is apparent that when the gas is turned on to supply gas to the burner 28, it will first pass into the chamber 12, and from this chamber will pass upwardly to the pilot burner orifice 54 and out through the slot 53 of the pilot burner. Gas will also pass through the conduit 48 into the chamber 44. Inasmuch as this gas is at higher than atmospheric pressure, the mercury within the chamber 44 and outside the tube 47 will be depressed to drive mercury up within the tube 47.

The mercury within the tube 47, when it reaches a sufficiently high level, contacts with the lower end of the electrode 45 and closes the circuit through the primary of the ignition transformer 34. The high voltage of the secondary winding causes an arc across the gap 33 to the grounded electrode 30 on the body 10 to ignite the gas issuing from the pilot burner 24.

The burning gas from the pilot burner heats the bi-metallic element 21 which raises the valve 16 from its seat to permit gas to flow into the chamber 13 and the main burner. As soon as this occurs the pressure within the chambers 12 and 13 is equalized and consequently the pressure within the chambers 44 and 46 of the switch is also equalized, which permits the mercury 38 to seek its own level and thus break the contact between the electrode 45 and the mercury 38. Breaking of the primary circuit of coil 34 stops the discharge of electricity across the gap 33.

It is apparent that gas is not admitted to the main burner until the pilot burner is ignited. Ignition of the pilot burner occurs only when gas is admitted to the supply inlet 11. As soon as the supply of gas is cut off, the burning of gas at the main burner and at the pilot burner ceases and the thermostat 21 cools to close the valve 16. As soon as the valve is closed, gas cannot be admitted to the main burner unless the pilot burner is ignited.

My invention is susceptible to numerous modifications; I may utilize only one transformer and pass a 110 volt circuit through the mercury switch 37, or may eliminate both transformers and pass the current direct through the mercury switch 37 and electrode 31.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a fluid fuel burner adapted to be operated in a substantially closed combustion space, a valve having inlet and outlet chambers, a main burner connected with the outlet chamber, a pilot burner connected directly with the inlet chamber, a means responsive to heat from the pilot burner for opening the valve, and switch means located outside the combustion space and responsive to differences in fuel pressure in the inlet and outlet chambers for controlling ignition of the pilot burner, said pilot burner being supplied with fuel from said inlet chamber independent of said switch means.

2. In a fluid fuel burner, a control valve having inlet and outlet ports, a gas supply line connected to the inlet port, a main burner connected to the outlet port, a pilot burner thermal control means activated by heat from the pilot burner for operating the control valve, electric

ignition means for the pilot burner, a differential pressure switch connected with the intake port and with the outlet port whereby an increase in pressure differential between fuel in the intake and outlet ports will close the switch 5 to energize the electric ignition means and whereby a decrease in the pressure differential

will open the switch and de-energize the ignition means said pilot burner being in direct communication with said supply line to receive gas continuously therefrom as long as gas is supplied to said gas supply line regardless of the position of said ignition means.

JOHN C. ENGLISH.
